UNITED STATES PATENT OFFICE.

ALEXANDER H. SHAW, OF MIDWEST, WYOMING.

FUEL BURNER.

Application filed February 13, 1926. Serial No. 88,082.

The present invention relates to improvements in fuel burners of the type wherein a blast or current of air is intimately mixed with fuel gas to produce a mixture adaptable for complete combustion.

An important object of the invention is to provide a burner of the above character of comparatively simple yet efficient design arranged to obtain complete combustion of the fuel gas.

A further object of the invention is the provision of a fuel burner arranged to produce an intimate mixture of the air and gas for efficient and economical operation.

Still another object of the invention is the provision of a burner wherein the air and gas will be uniformly mixed and at the same time present a structure designed to prevent premature destruction by the intense heat.

A still further object of the invention is the provision of a burner adaptable for firing furnaces and the like which will be efficient in use and can be manufactured at a comparably low cost.

Other objects and advantages of the invention will become apparent as the description progresses.

In the accompanying drawing forming a part of this specification and in which like numerals are employed to designate corresponding parts throughout the same:

Figure 1 is an end elevation of my improved burner structure taken from the interior of the combustion chamber, and

Figure 2 is a transverse sectional view taken on the line 2-2 of Figure 1.

Referring to the drawing, wherein for the purpose of illustration is shown the preferred embodiment of my invention, the numeral 10 generally designates a fragmentary portion of a wall of a combustion chamber provided with an annular opening for the introduction of a fuel burner. My invention contemplates the provision of an air duct 11 adapted to be arranged snugly in the opening of the combustion chamber wall having a uneven inner contour through which a current of air is injected. Arranged centrally in the air duct 11 is a gas burner generally indicated by the numeral 12, through which the fuel gas is distributed for mixture with the air in suitable proportion to produce complete combustion. Referring now more specifically to the construction embodying my invention, it

will be readily noted that the air duct 11 is of generally tubular formation and may be of metallic construction or, if desirable, may be formed of refractory material. The outer surface of the duct 11 may be of uniform cylindrical formation and arranged so as to be tightly fitted within the opening in the wall of the combustion chamber. The inner bore of the air duct is formed to provide a passage of decreased area adjacent the inner extremity, the purpose of which will become apparent as the description progresses. This is accomplished, in the present instance, by forming the duct with an interior annular ridge 13 having an abrupt shoulder at the intermediate portion of the air duct and gradually tapering toward the inner extremity which is rounded as at 14. From this construction, it is apparent, that the current of air passing through the air duct will be directed toward the center of the duct adjacent the inner extremity and is thus mixed with the gas, as will be presently seen.

Mounted so as to maintain a central position in the duct adjacent the inner end thereof is the burner 12 embodying a longitudinally extending gas supply pipe 15 supported in any conventional manner and communicating with a gas producer or any source of supply. The inner discharge end of this supply pipe which is of tubular formation, is of heavier construction to provide a nozzle 16, beveled at its extremity as at 17 and provided adjacent its opposite end with external screw threads 18.

Arranged to be threadedly mounted on the nozzle 16 and generally enclose the same is a bulbous oval shaped shell 19, one end thereof being open and provided with internal screw threads adapted for engagement with the threads 18 formed on the nozzle. As can be readily noted, with reference to Figure 2 of the drawing, an interior ring 20 is formed adjacent the open end of the shell to provide a durable structure for the formation of the threads. A transversely extending screw threaded bore 21 is formed through the reinforcing ring 20 and is adapted to engage a set screw for secure connection of the shell upon the nozzle. In order to permit suitable discharge of the fuel gas, the shell 19 is provided with a plurality of orifices or apertures 22 preferably formed in forwardly directed angular positions as shown to advantage in Figure 2. These ori-

fices may be arranged in equal spaced relation in circular formation in the intermediate portion of the shell as shown, or in staggered relation as found the most suitable for the efficient operation of the burner. It is readily evident, from the foregoing, that the particular relation of the shell upon the nozzle provides an expansion chamber for the fuel gas as the same issues from the nozzle and, an adjustable air passage is formed between the beveled end portion of the nozzle and the inner closed end of the shell.

In operation, it will be seen that as the current of air passes through the air duct 11 the air in its movement induces a flow of gas through the orifices 22 formed in the burner shell 19. Due to the arrangement of the burner in the air duct, the air and gas will be uniformly mixed as the gas is introduced into the air stream in the restricted area of the duct and thus produces an intimate mixture. As the gas issues from the discharge end of the nozzle and is circulated in the chamber formed by the shell, the expansion of the gas will result in a decrease in temperature. A similar effect is produced by the deflected current of air striking the outer surface of the shell. Assuming that a comparatively large proportion of gas is desired during a certain period of operation of the burner, this can be readily effected by turning the set screw threadedly mounted in the opening 21 of the shell so as to disengage the threads 18 formed on the nozzle, and the shell 19 suitably rotated to move the shell inwardly relative to the nozzle, or in a remote position from the end thereof. This will increase the area of the annular passage between the beveled end of the nozzle and the shell so that an increased flow of fuel gas is permitted into the expansion chamber formed by the shell and discharged through the orifices. The set screw is then screwed tightly into position in engagement with the nozzle to prevent further movement of the shell so that the predetermined mixture may be uniformly maintained. To reduce the proportion of the gas necessary for the complete combustion reverse rotary movement of the shell will reduce the amount of gas discharged for mixture with the air so that a greater proportion of air is employed in the mixture.

As will be readily noted, by those familiar with this art, a burner of improved design has been devised, providing means for producing an intimate mixture of air and gas to obtain complete combustion, and presenting a structure whereby unrestricted passage of the fuel is afforded. The particular formation and relative arrangement of the air duct and burner will cause the mixture of the air and gas to take place in a reduced portion of the air passage so that a thorough

mixture is obtained and the utmost efficiency of the fuel effected.

It is to be understood that the form of my invention herewith shown and described is to be taken as the preferred example of the same and that various changes as to the shape, size and arrangement of parts may be resorted to without departing from the spirit of the invention or the scope of the subjoined claims.

Having thus described my invention, I claim:

1. In a fuel burner, a supply pipe, a member adjustably associated with the supply pipe and arranged to provide an expansion chamber about the discharge end thereof, the said member being provided with a plurality of discharge orifices, and an air duct arranged in spaced relation laterally of the supply pipe provided with an annular inwardly projecting ridge adapted to form a restricted passage adjacent the orifices formed in the said adjustable member.

2. In a fuel burner, a supply pipe, a shell adjustably mounted on the supply pipe and arranged to form an expansion chamber about the discharge end thereof, the said shell being provided with a plurality of discharge orifices, and an air duct of annular formation arranged in spaced axial position relative to the supply pipe and shell provided with an annular ridge arranged to form a reduced passage adjacent the discharge orifices formed in the shell.

3. In a fuel burner, the combination of a burner including a discharge nozzle and an adjustable shell positioned about the discharge opening of the nozzle provided with discharge orifices, and an air duct arranged in spaced relation about the nozzle and shell provided with an annular interior ridge arranged to form a reduced passage adjacent the discharge orifices of the shell to form an intimate mixture of the fuel and air.

4. In a fuel burner, a supply pipe, a discharge nozzle formed on one end of the supply pipe, a shell of enlarged formation adjustably fitted about the discharge end of the nozzle, means for fastening the shell in adjusted position on the nozzle, the said shell being provided with a plurality of angular directed discharge orifices, and an air duct including a cylindrical tube arranged in axial spaced relation about the nozzle and shell having an annular inwardly extending ridge formed adjacent the orifices formed in the shell, the said ridge tapering toward the inner end of the duct for efficient passage of the mixture.

5. The combination with the combustion chamber of a furnace having an opening in the wall thereof; of a burner including a supply pipe, a shell arranged in spaced relation about the discharge end of the supply pipe, means for adjustably actuating the

shell in axial position relative to the discharge opening of the supply pipe, and adjustable means adapted to permit securing of the shell in adjusted position upon the discharge pipe; and an air duct of cylindrical formation arranged to be snugly fitted in the opening of the combustion chamber and provided with an annular inwardly projecting ridge adapted to direct the air blast in a reduced passage adjacent the discharge orifices of the burner shell.

6. In combination with a combustion chamber having an opening in one wall thereof, and an air duct snugly fitted in the opening provided with an annular interior ridge; a burner including a supply pipe ar-

ranged in a central axial position in the air duct, a shell of generally oval formation threadedly mounted adjacent the discharge end of the supply pipe arranged to form an expansion chamber about the discharge end of the pipe and adjustable relative to the discharge opening, means for locking the shell in adjusted position upon the supply pipe, the said shell being provided with a plurality of angular directed orifices arranged adjacent the ridge formed in the air duct so that the mixture of air and gas will be effected in a reduced passage formed in the duct.

In testimony whereof I affix my signature.

ALEXANDER H. SHAW.
